CLAIM

The ornamental design for a case for smart phone, as shown and described.

DESCRIPTION

FIG. 1 is a front perspective view of a case for smart phone, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled portion of FIG. 2 to more clearly disclose the pattern on the case.

The dot-dash broken lines in FIGS. 2 and 15 delineate a portion of the case that is part of the claimed design and that is shown on an enlarged scale in FIG. 15. The dashed broken lines and unshaded regions bounded by dashed broken lines form no part of the claimed design.
